presently in use, consisting of a roll of film, a developing bath, and a water bath, all of which are held in separate tanks. It is desired to eliminate the separate tanks and to combine the developing bath and the water bath into a single tank. A further object of the invention is to provide a tank which will be compact and which will be easily portable.

UNITED STATES PATENT OFFICE

2,344,998

PHOTOGRAPHIC TANK

Frank M. Morgan, Glen Ellyn, and Stanley Wallace, Chicago, Ill., assignors to Sears, Roebuck and Co., Chicago, Ill., a corporation of New York

Application October 5, 1939, Serial No. 297,976

1 Claim. (Cl. 95—90.5)

Our invention relates to photographic tanks for developing and other operations in the processing of roll film and is especially designed for use by amateurs.

An object of our invention is to provide a tank of the type referred to which may be molded entirely out of plastic material, which will be compact, convenient and, in general, entirely satisfactory for the purposes desired.

A particular object is to provide such a device which may be positively secured, when closed, in a lightproof condition.

Another object is to provide such a device which is readily adjustable so as to be capable of handling film of various widths.

Another object is to provide, in a device of the type referred to, a combined stirring rod and nozzle for washing purposes.

Various other objects and advantages will suggest themselves as the description proceeds.

Referring now to the drawings forming a part of this specification and illustrating a preferred embodiment of our invention:

Fig. 1 is a top plan view of a closed tank embodying our invention.

Fig. 2 is a sectional view on an enlarged scale taken substantially along the line 2—2 of Figs. 1 and 13.

Fig. 3 is a fragmentary elevational view of an upper portion of the tank, showing one form of cover connecting means.

Fig. 4 is an enlarged fragmentary sectional detail taken substantially along the line 4—4 of Fig. 3 and including in addition the tank cover.

Fig. 5 is a sectional view taken substantially along the line 5—5 of Fig. 4.

Fig. 6 is a top plan view of a tank provided with modified cover-securing means.

Fig. 7 is a fragmentary elevational view taken substantially as indicated by the line 7—7 in Fig. 6.

Fig. 8 is a somewhat enlarged fragmentary sectional view taken substantially as indicated by the line 8—8 in Fig. 7, with the cover added.

Fig. 9 is a fragmentary sectional view taken substantially as indicated by the line 9—9 in Fig. 8, on substantially the same scale as Fig. 7.

Fig. 10 is a fragmentary elevation showing details of the cover locking means of Figs. 6 to 9.

Fig. 11 is a sectional view taken substantially along the line 11—11 of Fig. 2.

Fig. 12 is an elevational view of a reel forming a part of our invention.

Fig. 13 is a sectional view taken substantially along the line 13—13 of Fig. 12.

Fig. 14 is a bottom plan view of the reel.

Fig. 15 is a fragmentary sectional view taken substantially along the line 15—15 of Fig. 13.

Fig. 16 is a fragmentary elevation of a reel assembly in which only one of the discs is provided with a film-checking gate.

Figs. 17, 18 and 19 are fragmentary plan views of modified film gates.

Fig. 20 is an elevational view of a modified stirring rod embodying features of our invention.

Fig. 21 is a fragmentary plan view of the "working" face of a modified reel disc.

Fig. 22 is an enlarged fragmentary sectional view taken as indicated by the line 22—22 in Fig. 21.

Figs. 23 and 24 are views similar to Figs. 21 and 22, respectively, but of a modified form of the invention.

The numeral 10 indicates generally a tank of a size suitable for the processing of roll film and having a cylindrical side wall 11 and an elevated bottom 12 with a depressed central portion 13 therein. The side wall 11 terminates at the top in a U-shaped portion 15 comprising flanges 15a and 15b separated by a channel 16.

We provide a closure means or cover 18 comprising a circular top wall 19 having a depressed cup-like portion 20 in the central portion thereof, the latter having a cylindrical downwardly extending flange 21. The cover has a cylindrical side wall 23 which extends within the flange 15a of the tank wall 11. The cover is also provided with a circular flange 25 which extends within the channel 16, and an outer rim portion 26 which seats outside of the flange 15b of the tank. The flange 26 is connected to the wall portion 23 of the cover by means of an annular web 27, a slot 28 being provided in the latter in registry with the channel 16 to serve as a pouring spout. As shown in Fig. 2, sufficient clearance is provided between the various elements of the closure adjacent the spout 28 to permit the passage of fluid.

The arrangement of the closure elements is such that the passage of light into the interior of the tank is effectively prevented.

Various means for locking the cover securely in place on the tank may be employed. Those shown in Figs. 2 to 5 and 6 to 10 are suitable examples.

As shown in Figs. 2 to 5, an L-shaped recess 30 provided on the outer surface of the flange 15b of the tank functions as a bayonet slot. The entrance 31 of the recess is of such a depth with

respect to the outer surface of the flange 15b as

to permit the ready passage of a protuberance or lug 32 formed on the inside of the flange 28 of the cover. Adjacent the area 31 is a raised portion 33 beyond which is an area 34 which, while deeper than the area 33, is, nevertheless, not as deep as the area 31. The area 34 is bounded by a sloping surface 35. Thus, it will be seen that when the tank is closed, the lug 32 will pass readily down through the area 31 and, upon rotating the cover to the left (Fig. 3), the lug will be required to pass over the high area 33 and then into frictional engagement with the area 34, the lug being cammed downwardly by the sloping surface 35. The cover is thus securely locked in place, since the lug 32 is not only frictionally engaged, but, furthermore, is required to be sprung past the positive obstruction of the area 33 before the cover can be removed.

Another bayonet type of connection is illustrated in Figs. 6 to 10, wherein the outer flange 38 of the container body has a smooth top 36a and the outer surface of said flange has ribs 37 spaced apart circumferentially as at 37a and having inclined lower edges 37b, and, on the web 31c, locating lugs 37d. Here, also, the cover has a smooth bottomed web 38 and, on the inside of its outer flange 39, a mutilated thread in the form of inclined ribs 39a spaced apart circumferentially as at 39b, locating lugs 39c being provided on the outer face of the flange 38 adjacent the lower ends of the ribs 39a. The cover is adapted to be lowered so that its web 38 rests on the body surface 36a, because the cover ribs 39a are adapted to descend in the body spaces 31c and, at the same time, the body ribs 37 will clear the cover spaces 39b. The cover is in position to descend when a locating lug on the cover is adjacent a locating lug on the body, and for this purpose the cover may be shifted in the dark to bring one of its locating lugs adjacent a locating lug on the body. After the cover web is lowered onto the body, the body is held while the cover is turned clockwise, for example, to lock the cover ribs against the rib edges 37b, thereby camming the cover tightly in place. Obviously the ribs could be arranged to require anti-clockwise movement of the cover for securing it in place.

The film retaining reel forming a part of our invention includes a pair of cooperating elements 40 and 41. The part 40 comprises a hollow spindle 42 which, as seen best in Figs. 11 and 13, is of an irregular hexagonal shape on the outside and has integral feet 43 extending into the well formed by the depressed portion 13 of the tank, the feet 43 being spaced apart and formed on a periphery permitting passage of fluid from the interior of the spindle 42 into the tank space 43. Integral with the spindle 42 is a disc 44 which may be provided with reinforcing ribs 45 and has a spiral flange 46 formed on the upper portion thereof, thus forming a spiral groove 47 within which a film F may be seated.

The upper reel part 41 comprises a sleeve portion 48 which, as shown best in Fig. 11, is of an eccentric hexagonal shape conforming to that of the spindle 42 and adapted to slide thereover. It will be understood, of course, that the spindle 42 and sleeve 48 may be of any eccentric shape so that they may be interfitted in only one relation. The purpose of this will appear shortly.

The sleeve 48 is slotted at 49 to seat a spring clip 50 formed of wire or the like, the seated portion 53 of the clip 50 extending inward and resiliently engaging selectively in any one of a series of recesses or grooves 55 which are pro-

vided at spaced intervals along the spindle 42. The grooves 55 are provided at definite intervals corresponding to the widths of standard roll film, so that the part 41 may be adjusted to any one of several fixed positions along the spindle 42, and the reel may thus be adjusted to accommodate a desired size of film.

Integral with the sleeve 48 is a disc 57 which is provided with a spiral rib 58 and associated groove 59 corresponding to the rib 46 and groove 47, respectively, of the lower disc.

As seen in Figs. 12 and 13, each of the discs is provided with an ear 60 adjacent which is a lug 61 defining therewith a peripheral gate or opening 62 through which film may be fed into or removed from the spiral groove 47. It will now be seen that the two parts 40 and 41 should be fitted together in only a certain relation, in order that the gates 62 may register so that the film may be conveniently inserted and removed through both gates simultaneously. The lug 61 serves as a stop or abutment to check escape of the outer end F' of the film F. The film-end engaging face of each lug may be at substantially a right angle to the end of the film as shown in Fig. 13. If desired, the lug may be omitted from one of the discs, as shown in Fig. 16, the other lug being relied upon to check the outer end F' of the film.

Instead of arranging the lug at substantially a right angle to the outer end F' of the film F, the lug may be at an acute angle as shown at 61a in Fig. 17, or in the form of a hook as at 61b independently of the rib 46 as shown in Fig. 18. Or, if desired, the lug could be omitted from each disc 30 and the projection 60a formed with an offset 60b against which the outer end of the film is adapted to abut, as shown in Fig. 19.

The discs 44 and 57 are provided with slots 63 to promote rapid flow of the liquid to the film.

40 The spindle 42 is provided with a neck 65 having a square or other non-circular opening 66 therein for the purpose of receiving an agitating rod 67 having a correspondingly shaped end portion 68 adapted to engage in the opening 66. In the form shown in Fig. 2, the stirring rod may be solid, having an enlarged handle portion 69 which may be knurled as at 70.

In another form, shown in Fig. 20, the agitator 50 rod 72 is hollow and shaped at the end portion 73 to engage in the neck 65 and may have a knurled portion 75. Extending beyond the knurled portion is a nipple 76 adapted to engage the end of a hose 77. This type of agitator may be employed for washing a film in the tank after it has been processed, the hose 77 being connected to a tap or the like. Also, a thermometer (not shown) may be inserted into the hollow rod when desired to check the temperature of the solution 55 in the tank.

60 A modified reel disc construction is shown in Figs. 21 and 22, wherein the bottom surface 80 of the spiral groove 81 of each reel disc 82 or of only the lower disc is circumferentially crowned 65 as at 84 so that only the peaks 85 of said surfaces engage the upper and lower edges F'' (or the lower edge) of the film F, thereby substituting a series of substantially point contacts for the line contact which obtains when said surfaces are 70 flat (Fig. 15), so as to minimize friction. Since in practice sufficient clearance between the discs is afforded to obviate binding of the edges of the film, it follows that because of gravity the brunt of the engagement of the film will be at 75 the lower disc, so that if desired only the film-

edge engaging groove bottom surfaces on the lower disc need be crowned.

With a view to still further minimizing engagement of the film by the reel, each or merely the lower disc may be formed with the inner face 87 of the rim 88 undulating circumferentially as shown in Figs. 23 and 24, providing lateral peaks or crests 89 affording a series of substantially point contacts with the outer side edge portions of the film F. These peaks may be located in register with or in any other desired relation to the floor peaks 85.

It is believed that the operation of the device described above will be readily apparent. The two parts 40 and 41 of the reel having been fitted together and adjusted to receive film of the desired size, the film will be fed into the reel through the openings 62 and into the registered spiral grooves of the reel discs, the reel then seated in the tank and the latter closed by securing the cover to the body. This operation, of course, will take place in the darkroom. After the cover is applied, the device may be taken into the daylight, if desired, and the developing fluid will be poured into the tank through the cup-shaped portion 20 and withdrawn by pouring it out of the spout 28. In the course of the development, the rod 67 or 72 will be arranged as shown in Fig. 2 and the reel rotated thereby to impart the desired amount of agitation. At the completion of the various steps of the processing, the cover may be removed and the film washed in any desired man-

ner with or without the cover in place. A hose from the tap may be connected to the hollow stirring rod of Fig. 20 with the cover in place, for the washing operation.

5 All parts of the apparatus may be molded out of Bakelite or other suitable plastic which is immune to the reagents of photographic processing, with the exception of the resilient clip 50, and this element also may be of such metal or other substance as is inert to such materials. It thus will be seen that we have provided a device which is simple, convenient, readily adjustable, and which has many advantages over devices of this type previously known.

10 Various modifications and changes coming within the spirit of our invention may suggest themselves to those skilled in the art, and, hence, we do not wish to be limited to the specific forms shown or uses mentioned.

15 We claim:

A developing tank having a film-holding reel rotatably disposed therein, means for rotating said reel, said means comprising a hollow rod slidably and detachably engageable at one end with said reel and having means at the other end for detachably anchoring a hose, said rod having knurled means thereon engageable by the operator to facilitate rotary manipulation while the hose is anchored to said anchoring means.

20 FRANK M. MORGAN.
STANLEY WALLACE.
